UNITED STATES PATENT OFFICE.

ARTHUR H. DU GRENIER AND JAMES H. MCPHERSON, OF HAVERHILL, MASSACHUSETTS.

BLADE-VENDING MACHINE.

1,231,243.

Specification of Letters Patent. Patented June 26, 1917.

Application filed April 26, 1916. Serial No. 93,790.

To all whom it may concern:

Be it known that we, ARTHUR H. DU GRENIER, a subject of the King of Great Britain, and JAMES H. MCPHERSON, a citizen of the United States, both residing at Haverhill, in the county of Essex and State of Massachusetts, have invented an Improvement in Blade-Vending Machines, of which the following is a specification.

10 This invention relates to check or coin-controlled vending machines, and more particularly to a machine designed to be employed in shoe factories, to vend shoe-cutters' knife blades.

15 Inasmuch as various makes and styles of shoe-cutters' blades are employed, it is practically necessary that a machine for vending such articles be arranged to deliver to the purchaser any one of a number of different

20 kinds of blades, in practice, about eight different varieties being sold.

The object of our invention is to produce a form of vending machine which is primarily adapted to vend various styles and 25 forms of shoe-cutters' blades, although it may be employed for vending a variety of other articles of merchandise, and which is of simple and durable construction, and which answers all of the well-known requirements of machines of this character.

We accomplish these objects by the means shown in the accompanying drawing, in which;

Figures 1 and 2 are respectively front 35 and side elevations of a vending machine embodying our invention.

Fig. 3 is a sectional view taken at the line *a—a* of Fig. 5.

Fig. 4 is a rear elevation of the machine. 40 Fig. 5 is a vertical sectional view taken at the line *b—b* of Fig. 1.

Fig. 6 is a detail view of the ejector-mechanism taken from the left-hand side of the machine.

45 Fig. 7 is a similar view taken from the right-hand side of the machine.

Fig. 8 is a view similar to Fig. 7, showing the parts in a different position.

Fig. 9 is a detail view partly in section 50 at the line *c—c* of Fig. 8.

Fig. 10 is a detail view of the coin-testing device.

Figs. 11, 12, and 13 are detail views of the coin-testing and rejecting mechanism, showing the parts in different positions. 55

Fig. 14 is a detail view of the article to be vended.

As shown in the drawing, the casing 1, which contains all of the operative parts of the machine, is hinged to a back-board 2, 60 adapted to be secured to the wall, said casing being locked in position against the back-board by means of a padlock 3, or other suitable means, so that the whole casing may be swung away from the wall, as indicated 65 in Fig. 4, to expose the mechanism for the purpose of refilling, and to permit the removal of coins therefrom.

For the purpose of indicating the different forms of blades which the machine is to 70 vend, a dial plate 4 is provided on the face of the casing, in the center of which a crank 5 is mounted on a central shaft 6, and about which, openings 4^a are arranged, provision being made for the insertion of cards, on 75 which, characters, indicating the different kinds of blades to be vended, may be written, in the rear of said openings, so that the characters will be visible. The crank 5 is provided with a handle 7, which is mounted on 80 a spring-pressed pin, which slides in the handle to engage any one of a series of apertures 4^b on the dial, disposed adjacent the indicating openings 4^a.

Within the casing, a carrier 8 is mounted 85 on the shaft 6, to rotate therewith, and comprises a series of radially-extending arms 8^a, on each of which a casing or compartment 9 is removably secured, said compartments being arranged approximately radially with 90 relation to the axis of the shaft 6, and equally spaced apart, with the bottoms thereof in the periphery of a cylinder having its axis coincident with the axis of shaft 6.

As the articles to be vended are not of 95 convenient form to be handled by a machine of this character, each blade *x* is mounted on a flat, oblong strip of wood *y*, and secured at one side thereof by strips of paper *z*, so that it may be readily removed, as in- 100

dicated in Fig. 14. Each compartment 9 is shaped, in transverse section, to receive the wooden strips y , so that a stack of said strips, with the blades attached thereto, may be placed in each compartment of the carrier, and may rest on the bottom 9^a thereof, as indicated in Figs. 5 and 8.

A weighted follower 10, of approximately the same shape as the wooden strips y , is provided in each compartment, said follower being provided with a pair of end lugs 10^a, and a middle lug 10^b, which depend from the outer or under side thereof, to the same extent, the middle lug being extended laterally from the follower, as indicated in Fig. 9, and inclined on its under side, for a purpose to be hereafter explained. A longitudinal groove 10^c is provided on the inner side of the follower, and a pair of spring-actuated levers 12 are mounted on pivots 13, at opposite ends of each compartment 9, said pivots being located adjacent the upper or inner ends of said levers, so that a pair of long arms are provided, which extend cross-wise of each other, and rest at their ends in the groove 10^c of the follower, while the short arms thereof are connected by a spring 14, which acts to draw them together, and thus force the ends of the long arms, and therefore the follower which they engage, radially outward, or toward the bottom of the compartment. Each spring 14 is of sufficient strength to overcome the gravity of the follower and of a stack of blades and holders of any height which a compartment may contain, so that the stack will be held in position in all positions of the carrier, and when the last blade has been removed from a compartment, the follower therein will be held against the bottom thereof. The relative arrangement of the crank 5 in the compartments 9 is such that, when the crank is swung to any one of the positions in which it is adapted to be locked, the carrier will be rotated so as to bring the corresponding compartment into the vertical position directly beneath the axis of the shaft 6, in which position each compartment must be held, in order that the ejecting mechanism, hereafter described, may operate to move the articles therefrom. The bottom 9^a of each compartment has transverse slots 9^b and 9^c formed therein, which extend entirely across the same and correspond in position to the position of the lugs 10^a and 10^b of the follower, so that, when a compartment is empty, said lugs will extend through said slots, beyond the bottom. The end lugs 10^a have no important function, other than to provide engaging means for the stack at the ends of the followers, which are level with the middle lug 10^b. A discharge slot 9^d is also provided in one side of each compartment next the bottom 9^a thereof, the width of said slot

being slightly greater than the thickness of 65 a blade and holder.

The form of ejecting mechanism which is employed in this connection comprises a pair of arms 16 which are mounted on a shaft 17 supported in fixed lugs, said arms each 70 having a dog 18 pivoted on the end thereof and arranged to pass through the slots 9^b, in the bottom of each compartment, when in ejecting position, and to engage the bottom article of a stack, to slide the same from beneath it, through the discharge slot 9^d, springs 19 being connected to each dog, which permit them to swing downward on the return movement, and to return them to operative position. A link 20 is connected, 80 at one end, by a universal joint, to the arms 16, and at the other end by a similar joint, to the end of an arm 22, which is mounted on a shaft 24, arranged at right angles to the pivot 17 of the arms 16, so that when the 85 shaft 24 is rotated in the direction of the arrow in Fig. 6, the arm 22 will be swung upwardly pushing the link 20 in the same direction, and causing the arms 16 to swing from right to left, so as to eject the article. 90

In order that the carrier may be positively locked, while the ejecting mechanism is being operated, a finger 26 is pivotally mounted on the arm 22, and is arranged to extend upwardly, in position to enter a notch 95 8^b, formed in the peripheral portion of each arm 8^a of the carrier, to lock the latter against rotation.

The main shaft 28 of the ejector mechanism is mounted in the casing beneath the shaft 24, and extends outside the casing to receive an actuating handle 29. A flat metal operating plate 30 is rigidly mounted on the shaft 28, to swing in a plane at right angles thereto, and is provided with an arc-shaped peripheral portion, on which a series of ratchet teeth 30^a are formed, a pawl 32 being mounted on a fixed portion of the machine, in position to engage said teeth, so that when the handle 29 has been turned to a certain extent in a direction to operate the ejecting mechanism, the operation must be finished before the pawl 32 will permit the parts to be returned to initial position. The plate 30 is arranged to swing between a pair of flat partitions 36, 38, in close proximity thereto, and also in the plane of a coin-entrance-slot 1^a, which is formed in the front of the casing, said slot being of the same size as the coin, in connection with which the machine is designed to operate, and the width of the space between said partitions being sufficient to permit the coin to pass readily therebetween. Said plate 30 is further provided with a shoulder 30^b, which extends adjacent the inner side of the casing, and, in the normal position of said plate, is held adjacent the upper end of the 110 115 120 125

slot 1^a, and an arc-shaped edge-portion 30^c extends from said shoulder and forms one side of the coin passage, which leads from the entrance slot 1^a.

- 5 A partition 31 is arranged to extend from one side of the casing to the other and to extend upwardly to a point beneath the lower end of the arc-shaped portion 30^c of the plate 30, said partition acting to form 10 the bottom of a coin-receiving receptacle, and also the inner side of a passage 33 for rejected coins, the upper end of which is practically continuous with the lower end of the coin entrance passage and the lower 15 end of which opens to a cup 34, into which a coin, falling down said passage, 33, will be discharged. That is, unless intercepted, a coin inserted in the slot 1^a, will immediately fall into the cup 34.
- 20 Coin-intercepting means are, however, provided for directing the coin into the receptacle formed by partition 31, said means comprising a support 40, which is suspended on a pivot 41, mounted in a lug 36^a, on 25 partition 36, to swing transversely of the plate 30, and on which a coin-tester 42 is supported by a pivot 43 in a position at right angles thereto, so that it extends directly across the coin entrance passage be- 30 tween the partitions 36 and 38, directly beneath the lower end of the arc-shaped portion 30^c of the plate 30, as shown in Fig. 11. A finger portion 30^d is formed on plate 30, the outer side of said arc-shaped portion 35 30^c extending thereon and said finger portion terminating at a distance from the upper surface of the coin tester 42, slightly less than the diameter of the coin, which the machine is designed to receive, and at 40 a point to one side of the pivot 43, so that, under normal conditions, when the coin falls down the entrance slot, it will be intercept- ed by the coin tester 42, and will roll along on the surface, past the pivot thereof, until 45 it is intercepted by the finger portion 30^d, in the dotted position indicated in Fig. 5, and if the disk which has been inserted is of less weight than that of the standard coin, it will lodge at that point, but if it is 50 of standard weight, it will overbalance the opposite end of the tester 42, and, as the latter tilts down, it will be permitted to pass beneath the finger 30^d, into operative relation with the article-ejecting operating 55 mechanism.

The mechanism directly coöperating with the coin consists of an arm 45 rigidly mounted on the shaft 24 and having its end 45' concaved to receive the coin, and a finger 60 on the plate 30 having a correspondingly concaved end 30^e. The concaved end of the arm 45 is normally held in position to receive the coin, as it is discharged from the coin tester 42, and the coin is retained there-

in by a fixed finger 46, which is mounted 65 on the partition 31 and extends upwardly therefrom, between the partitions 36 and 38, to a point beneath the coin tester 42, at which point the coin-receiving passage branches from the coin-entrance passage. 70 A magnet 47 is provided in the partition 38 which will retain a magnetic slug falling on the tester 42. A lug 40^a projects from the inner side of the support 40, into the path of movement of the finger 30^d, so that 75 when the plate 30 is swung forwardly and downwardly, it will engage said lug 40^a and swing its support 40 aside so as to withdraw the coin tester 42 from the coin passage and open the coin entrance passage to the re- 80 jecting passage, as shown in Fig. 12. A lug 40^b on said support acts to hold it in its normal position of Fig. 11.

An arm 52 is pivoted, at one end, on the casing and a roll 54 is rotatably mounted 85 on the free end thereof, said roll having a grooved periphery and being arranged in the plane of the path of movement of the middle lug 10^b, of the followers, so that when a compartment becomes empty, and 90 the follower 10 therein therefore rests on the bottom thereof, the lug 10^b on the follower will pass into the peripheral groove of the roll 54, as the carrier brings said compartment into the ejecting position, the 95 inclined projecting end-portion of said lug 10^b enabling it to ride up onto the roll readily. The roll is thus caused to be depressed against the action of a counter-balancing lever 58, which normally supports said roll, 100 so that its periphery lies in the path of movement of the lug 10^b. A rod 55 is suspended from the end of the arm 52 and ex- 105 tends downward in position to engage one arm 56 of a lever, which is pivotally sup- ported on partition 36, the other arm 57 of which depends in position to engage the inner side of support 40, the arrangement being such that the rod 55 is normally sup- 110 ported in contact with arm 56, but without substantial pressure thereon, so that when the rod is depressed, through the depression of the roll 54, by a follower 10, it will force down the arm 56, causing the arm 57 to swing outward against the support 40, and force the latter aside, as shown in Fig. 13, 115 withdrawing the coin tester 42 from the coin-entrance passage and opening com- munication between said passage and the coin-rejecting passage, as already described. 120

The rear ends of the compartments 9 are preferably provided with doors 9^e, which are hinged at the bottoms thereof, so that they may be swung down to permit the articles to be vended to be readily inserted. The casing is provided with an inclined de- 125 liver chute 60, at one side of the ejecting position of the compartments, said chute

leading to an opening 1^c in the side of the casing.

The operation of the machine is as follows:

5 The operator first turns the crank 5 to the position corresponding to the particular form or kind of blade which he wishes to secure, and then inserts the coin, in the present instance a dime, which rolls down 10 the receiving passage on the plate edge-portion 30^c, onto the coin tester 42, and against the finger 30^a. If the coin is of standard weight, the coin tester then tilts, and discharges it, so that the coin lodges against the 15 end of the arm 45, as shown in Fig. 7. The handle 29 is then rotated forwardly, so that the plate 30 is swung forwardly and downwardly, bringing the finger 30^a into engagement with the upper edge of the coin, which, 20 for the time being, becomes part of the mechanism, so that continued movement of the handle causes the arm 45 to be swung rearwardly until the coin is finally pushed from between the arm 45 and finger 46, and 25 falls onto the plate 31, where it may later be recovered. This movement of arm 45 causes corresponding rotation of the shaft 24, so that the carrier is locked against rotation by the finger 26, and the arms 16 are 30 swung so that the bottom article of the stack, in the particular compartment which has been moved to ejecting position, will be pushed laterally from beneath the stack and into the delivery chute 60 of the machine, 35 down which it will slide through the opening 1^c. During the initial movement of the plate 30, the finger 30^a thereof engages the lug 40^a and moves the support 40 aside sufficiently to withdraw the coin tester 42 from 40 the entrance passage, so that, in case a coin of underweight has been intercepted by the coin tester 42, it will be discharged into the rejected-coin-passage 33, and fall into the cup 34.

45 Or, in case a slug is retained by the magnet 47, so that it does not fall into the passage 33, after the coin tester has been moved from beneath it, the slug will be engaged by the shoulder 30^b and swept into said passage, 50 and, at the same time, any foreign matter, which may have been pushed through the entrance slot, will be carried down by said shoulder portion of the plate 30, so that the coin entrance passage is cleared each time 55 the machine is operated.

In case the compartment which is moved into ejecting position is empty, its follower 10 will cause the support 40 to be moved aside, as shown in Fig. 13, so as to open 60 communication between the entrance and rejecting passages, as already described, so that when the coin is inserted, it will immediately fall down into the cup 34, where it may be recovered.

The various parts are provided with 65 springs for returning them to initial position, when the operation is finished, a spring 62 being attached to the arm 45, and a spring 63 to an arm 64 on shaft 28 for this purpose.

70 From the foregoing description it will be apparent that the machine can only be operated when one of the compartments of the carrier is held in the ejecting position and contains at least one article to be delivered and unless a check of a size, weight, and strength corresponding to the standard coin, which the machine is designed to receive, is inserted.

75 We claim:—

1. A vending-machine having a coin-entrance passage, a coin-rejecting passage and a coin-receiving passage leading therefrom, a coin-tester normally arranged to close communication between said entrance and said rejecting-passages, and tiltable by the gravity of a coin of predetermined weight to deliver the coin to said receiving-passage, and manually-controlled means to move said coin-tester bodily to one side of its normal position to open communication between 80 said entrance and rejecting-passages.

85 2. A vending-machine having a coin-entrance passage, a coin-rejecting passage and a coin-receiving passage leading therefrom, a coin-tester normally arranged to close communication between said entrance and said rejecting-passages, and tiltable in one direction by the gravity of a coin of predetermined weight, to deliver the coin to said receiving-passage, and manually-controlled 90 means for moving said coin-tester in a different direction to open communication to said rejecting passage.

95 3. A vending-machine having a coin-entrance passage, a coin-rejecting passage and a coin-receiving passage leading therefrom, a pivotally supported coin-tester normally arranged to close communication between 100 said entrance and rejecting-passages, and adapted to be tilted by the gravity of a coin of predetermined weight, to deliver the coin to said receiving-passage, manually-controlled means, and means, operated by said means, on operative movement thereof, for moving said coin-tester to open communication 105 between said entrance and rejecting-passages.

110 4. A vending machine having a coin-entrance passage, a coin-rejecting passage, and a coin-receiving passage leading therefrom, a pivotally-supported coin-tester normally supported to close communication between 115 said entrance and rejecting-passages, and adapted to be tilted by the gravity of a coin of predetermined weight to deliver the coin to said receiving-passage, manually-controlled means, and means, operated by 120 means, on operative movement thereof, for moving said coin-tester to open communication between said entrance and rejecting-passages.

125

90

95

100

105

110

115

120

125

5. A vending-machine having a coin-entrance passage, a coin-rejecting passage, and a coin-receiving passage leading therefrom, a support having a coin-tester pivotally mounted thereon and arranged normally to close communication between said entrance and said rejecting-passages, and to be tilted by the gravity of a coin of predetermined weight, to deliver the coin to said receiving-passage, and means to move said support to carry said coin-tester bodily to a position in which free communication between said entrance and rejecting-passages is permitted.
6. A vending-machine having a coin-entrance passage, a coin-rejecting passage, and a coin-receiving passage leading therefrom, a coin-tester normally arranged to close communication between said entrance and said rejecting-passages, and tiltable by the gravity action of a coin of predetermined weight to deliver the coin to said receiving-passage, manually-controlled means, and means actuated by said manually controlled means, during the initial portion of its operative movement, to move said coin-tester bodily to one side of its normal position, to open communication between said entrance and rejecting-passages.
7. A vending-machine having a coin-entrance passage, a coin-rejecting passage, and a coin-receiving passage leading therefrom, a coin-tester normally arranged to close communication between said entrance and said rejecting-passage, and tiltable by the gravity action of a coin of predetermined weight to deliver the coin to said receiving-passage, an actuator, manually-controlled operating-means, and means, controlled by said operating-means, to move said coin-tester to one side of its normal position and open communication between said entrance and rejecting-passages, and to operate said actuator, through the instrumentality of the inserted coin, successively.
8. In a vending-machine having a compartment adapted to contain a stack of articles to be vended, a follower adapted to rest on the top of such stack and at the bottom of the compartment when empty, coin-controlled apparatus including a coin-tester arranged to be moved in one direction by the gravity of a coin of predetermined weight, to retain the coin, and to be moved in a different direction to reject it, and means arranged to be operated by said follower, when at the bottom of its compartment, to hold said coin-tester in its coin-rejecting position.
9. In a vending machine having a downwardly-extending coin-entrance passage, a coin-rejecting passage into which said entrance passage leads, and a coin-receiving passage branching therefrom, a coin-deflector normally supported in a position to close communication between said entrance and rejecting passages, a manually-controlled operating-device, and means, arranged to be actuated by said operating-device, when moved from initial position, to move said deflector to permit a coin thereon to pass into said coin-rejecting passage.
10. In a vending machine having a coin-entrance passage and a coin-rejecting passage leading therefrom, an operating-handle having a slot-clearing device arranged to be moved through said entrance passage, on operative movement of said handle, to force the contents thereof into said coin-rejecting passage.
11. In a vending machine having a downwardly-extending coin-entrance passage, a coin-rejecting passage into which said entrance passage leads, and a coin-receiving passage branching therefrom, a coin-deflector normally supported in a position to close communication between said entrance and rejecting passages, a manually-controlled operating-device, means arranged to be carried longitudinally of said entrance passage, to clear the same, on operative movement of said operating-device, to move said deflector to open communication between said entrance and discharge passages.
12. A vending machine having a coin-entrance passage, a coin-rejecting passage to which said entrance passage leads, and a coin-receiving passage branching therefrom, a coin-tester normally supported to close communication between said entrance and rejecting passages and to be tilted longitudinally by the weight of the coin, to deliver it to said receiving passage, and means to move said coin-tester laterally to open communication between said entrance and rejecting passages.
13. A vending-machine having a continuously-disposed coin-entrance and coin-rejecting passage, and a coin-retaining passage branching therefrom, a coin-tester normally arranged to prevent entrance of a coin to said rejecting passage, and tiltable by the gravity action of a coin of predetermined weight to deliver the coin to said retaining-passage, operating-means, a slot-clearing device, and means, actuated by said operating-means during the initial portion of its operative movement, to move said slot-clearing device through said entrance passage and to move said coin-tester bodily to one side of its normal position, to permit discharge of the contents of said entrance passage into said rejecting passage,

14. A vending-machine having a downwardly-extending, main coin-passage arranged to receive a coin at the upper end and return it at the lower end, and a coin-
5 retaining passage branching laterally therefrom, and a pivotally-supported coin-testing plate normally arranged to close said main passage, and to be tilted by the gravity of a coin of predetermined weight, to deliver
10 the coin into said retaining-passage, and

bodily movable with its support to permit a coin, supported thereby, to pass to the lower end of said main passage.

In testimony whereof, we have signed our names to this specification.
